E. AMIES

SPRING MATTRESS

Filed Aug. 16, 1921

INVENTOR.

Edwin Amies.
For
A. Milward Flack
his Attorney.

UNITED STATES PATENT OFFICE.

EDWIN AMIES, OF LONDON, ENGLAND.

SPRING MATTRESS.

Application filed August 16, 1921. Serial No. 492,756.

To all whom it may concern:

Be it known that I, EDWIN AMIES, a subject of the King of Great Britain and Ireland, residing at 46 Priory Road, Bedford 5 Park, London, England, have invented an Improvement in Spring Mattresses (for which I have filed an application in England, August 7th, 1920, application No. 28251), of which the following is a specification.

This invention relates to a new or improved spring mattress, applicable also to seats for vehicles and for furniture and like purposes and comprises certain improvements in that type of mattress in which a plurality of arched steel strips or wires with or without interposed springs, or strips bent to a spring like formation are each held singly and parallelly in the members of a 15 rectangular frame and the primary object of the present invention is to produce a highly efficient mattress or resilient surface at a minimum expense.

A convenient construction comprises essentially a rectangular frame, a plurality of vertically arranged holes or pockets in the side and end members of said frame, a plurality of spring steel wires each of an arched shape and approximating in length to the 20 width of the frame and having the ends of each wire inserted within the holes or pockets in the side members of the frame, a plurality of spring steel wires each of an arch shape and approximating in length to the 25 distance between the end members of the frame and having the ends of each wire inserted within the holes or pockets in the end members after each wire is first threaded over and under the transverse 30 wires.

This invention also contemplates the use of spring like edges to the frame, formed from arched steel wires and also a canvas or like material covering for the spring 35 wires in combination with an overlay or mattress of hair or other suitable material.

A further feature of the invention, in the case of an extra wide mattress for double beds for instance, is the provision of additional transverse wires about the centre 50 to avoid any sagging at such central part.

This invention will now be more particularly described making reference to the accompanying drawing in which:

Fig. 1 is a broken view in plan of a spring

mattress constructed according to the present invention;

Fig. 2 is a view in transverse section thereof;

Fig. 3 is a broken view in plan of a double 60 width spring mattress.

Fig. 4 is a view in transverse section thereof;

Fig. 5 is a detail view in section—on an enlarged scale—showing the one end of one 65 of the wires fitted within one of the holes or pockets in the members of the frame.

Fig. 6 is a similar view of a modification.

Fig. 7 is a broken view in plan thereof;

Fig. 8 is a view in transverse section—on 70 an enlarged scale—showing more particularly the formation of the spring edge, and

Fig. 9 is a view in end elevation of a complete spring mattress with its overlay.

Throughout the views similar parts are 75 marked with like letters of reference.

Referring more particularly to Figs. 1 and 2, a rectangular frame composed of end members a and side members a^1 is provided on its upper surface with a plurality 80 of substantially equally spaced holes or pockets a^2 —which may well be about four inches apart—adapted to receive the ends b of arch shaped wires.

These wires are preferably of coppered, 85 tinned or plated spring steel (of any appropriate gauge No. 9 or 11 S. W. G. is eminently suitable and satisfactory in practice) and are simply cut off to an appropriate length from a coil of wire and their ends 90 inserted in the holes or pockets without bending, their curvature being due solely to the form imparted to the wire on reeling or making it into coils for transport.

The transverse wires b^1 are preferably 95 first placed in position then the longitudinal wires b^2 are passed alternately under and over the transverse wires before their ends are positioned in the holes or pockets in the end members a . The longitudinal 100 wires b^2 may be indented or bent at the crossing points with the transverse wires b^1 in order to stiffen and brace the latter or the crossing points of the wires may be bound together. The ends b of the wires

105 may be simply inserted within pockets formed in the members of the frames, but preferably the following method (see Fig. 5) is adopted. A hole a^2 somewhat larger 110 than the wire employed, is first drilled to a

suitable depth, which is then counter bored to receive a steel disc or washer c provided with a central hole approximating to the gauge of wire employed, the end b of the 5 wire is then thrust through this disc or washer, its end resting on the bottom of the hole. The frame may be made from wood, which is the case in the construction above described, but it may equally well be made 10 from metal (see Figs. 6 and 7) preferably of a channel section in which case snugs or inwardly formed depressions d are formed in the vertical web d^1 . These snugs d are provided with or form holes or pockets to 15 receive the ends b of the wires which first pass freely through slots d^2 formed in the upper flange d^3 as shown. If angle iron or metal be employed, a stop is provided for the extremity of the wire.

20 In the case of a mattress for a double bed the construction illustrated in Figs. 3 and 4 is preferably employed, in which case the frame is furnished with two additional longitudinal members a^1 a^3 arranged as 25 shown. Each of these members are provided with holes or pockets a^2 , the one series in the members a^1 and a^3 being alternately arranged with respect to the series in the other member a^1 and a^3 so that the 30 transverse wires b^1 extend from one of the side members a^1 to the additional member a^3 furthest from it. By this arrangement the central portion of the mattress between the members a^3 a^3 contains double the 35 number of transverse wires as shown and so effectually prevents any sagging in the centre of the mattress.

40 In order to provide a spring edge to the mattress, additional arch shaped wires b^3 may be arranged alternately as shown (see Fig. 8) on each end and side member of the frame. The ends of these wires are

placed within holes or pockets in the members of the frame and the highest points of these wires are slightly higher than the 45 height of the transverse and longitudinal wires b^1 b^2 .

Flexible rods, such as cane e , (see Fig. 9) are secured to these arch shaped wires b^3 by binding with twine or wire and over 50 the whole is placed a textile covering f of canvas or other suitable material which may be tacked or nailed to the members of the frame, if of wood, or in the case of metal, to wood filets secured within the 55 channel or angle section, or the covering f may be removably attached by eyelets and buttons g secured to the underside of the frame. Over this covering is placed or attached thereto an overlay f^1 filled with 60 horse hair or other suitable filling. The covering or the overlay may be secured by twine to the wires and the overlay buttoned as usual.

In some cases provision may be made for 65 making the longitudinal members of the frame in two parts hinged together for convenience in transport.

I declare that what I claim is:—

A spring mattress comprising a rectangular metallic frame formed of channel section members, inwardly projecting snugs formed on the vertical webs of said members, vertical pockets formed in said snugs, slots formed in the upper flanges of said 75 members in line with the pockets in said snugs, and a plurality of longitudinal and transverse resilient members formed by cutting off appropriate lengths of steel wire from a coil and having their ends inserted 80 through the slots and within the pockets in the snugs, as set forth.

EDWIN AMIES.
